UNITED STATES PATENT OFFICE.

JOHN BRUCE HOUGH, OF ERVING, MASSACHUSETTS.

DESIGN FOR A TROUSERS-HANGER.

SPECIFICATION forming part of Design No. 35,527, dated December 31, 1901.

Application filed October 26, 1901. Serial No. 80,157. Term of patent 14 years.

To all whom it may concern:

Be it known that I, JOHN BRUCE HOUGH, a citizen of the United States, residing at Erving, in the county of Franklin and State of Massachusetts, have invented and produced a certain new and useful Design for a Trousers-Hanger; and I do hereby declare the following to be a full, clear, and exact description of the invention, such as will enable others skilled in the art to which it appertains to make and use the same.

My invention is a design for a trousers-hanger; and it consists in the shape and configuration hereinafter fully described, and illustrated in the accompanying drawing.

The drawing is a perspective view of a trousers-hanger embodying the design, and it comprises a single piece of wire bent centrally to form a loop 1, having diverging sides 2 and 3, and thence bent in opposite direc-

tions, forming horizontal arms 4. The outer ends of these arms 4 are bent inward upon themselves, forming curved bends 5 and inwardly-projecting arms 6, which latter are bent at the points 7 to form forwardly-projecting oppositely-disposed inclined extremities 8.

The leading features of the design are the oppositely-extending arms 4, the curved bends 5, the inwardly-extending arms 6, and the forwardly-projecting extremities 8.

I claim—

The design for a trousers-hanger herein shown and described.

In testimony whereof I affix my signature in presence of two witnesses.

JOHN BRUCE HOUGH.
